UNITED STATES PATENT OFFICE.

PERCY JACKSON, OF MACON, GEORGIA, ASSIGNOR TO J. S. SCHOFIELD'S SONS CO., OF MACON, GEORGIA.

RETORT.

No. 832,976.

Specification of Letters Patent.

Patented Oct. 9, 1906.

Application filed October 11, 1905. Serial No. 282,264.

To all whom it may concern:

Be it known that I, PERCY JACKSON, a citizen of the United States, and a resident of Macon, in the county of Bibb and State of Georgia, have invented a new and Improved Retort, of which the following is a full, clear, and exact description.

The invention relates to the destructive distillation of wood and like material; and its object is to provide a new and improved retort more especially designed for extracting turpentine from pine wood and arranged to permit of conveniently loading or charging the retort with the wood to insure proper destructive distillation of the wood and to allow quick dumping of the residue after the extracting process is completed.

The invention consists of novel features and parts and combinations of the same, which will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement on the line 1 1 of Fig. 2, showing the retort in the position for filling. Fig. 2 is a sectional plan view of the same on the line 2 2 of Fig. 1. Fig. 3 is an enlarged sectional side elevation of the device for fastening the cover in position on the body of the retort. Fig. 4 is a reduced sectional plan view of the same on the line 4 4 of Fig. 3, and Fig. 5 is an enlarged sectional plan view of the steam-inlet trunnion.

The vessel A of the turpentine apparatus is preferably made cylindrical, permanently closed at one end, and provided at the other end with a removable cover B to allow of filling the vessel A with the wood to be treated at the time the vessel A is in a vertical position, as shown in Fig. 1, the said cover when removed also allowing dumping of the residue after the extracting process is completed and the retort is swung into an inverted position—that is, with the cover B lowermost. The vessel A is provided on its sides with hollow trunnions C and D, mounted to turn in suitable bearings E and E', and on the trunnion C is secured a gear-wheel F, in mesh with a pinion F', secured on a shaft F'', adapted to be turned so as to rotate the gear-

wheel F and the trunnion C with a view to swing the vessel A either into a vertical position, as shown in Fig. 1, and with the cover B uppermost for filling the vessel A with the wood or to swing the vessel A into a horizontal position during the time the process of distillation is carried out or to swing the vessel A into an inverted vertical position with the cover B lowermost for dumping the residue incident to the process of distillation.

The trunnions C and D are provided at their outer ends with stuffing-boxes C' and D', through which extend pipes G and H, of which the pipe G is connected with a boiler or similar source of steam-supply and the pipe H is connected with a condenser or like apparatus for carrying the vapors arising from the destructive distillation to the condenser for further treatment. The hollow trunnion C is provided with an outlet C'', connected by a pipe I with a branch pipe J', arranged within the vessel A and connected with perforated pipes J, extending lengthwise in the vessel A adjacent to the inner surface thereof, as plainly indicated in Figs. 1 and 2. By the arrangement described the steam passing through the pipe G enters the hollow trunnion C and passes by the outlet C'', pipe I, and branch pipe J' into the perforated pipes J, to then pass into the interior of the vessel A to act on the wood contained therein with a view to extract the turpentine contained in the wood. It is understood that steam is admitted to the pipes J at the time the vessel A is in a horizontal position, and the pipes J extend along the bottom of the vessel.

The trunnion D has an inlet D'', connected by a pipe K with the interior of the vessel A at a point directly opposite the pipes J, so that when the vessel A is in a horizontal position and steam is admitted to the same, as above described, then the vapors arising from the process of distillation pass into the pipe K at the top of the vessel A to finally pass through the trunnion D into the pipe H to be carried to a condenser or other apparatus.

The cover B is removably held on the end of the vessel A, preferably by the use of eye-bolts L, and in order to insure a tight joint between the cover B and the end of the vessel A, I provide the cover with an annular V-shaped rib B', fitting a correspondingly-

shaped annular groove A', arranged at the end of the vessel A, (see Figs. 1 and 3,) a suitable packing N being preferably interposed between the bottom of the rib B' and the bottom of the groove A'.

The operation is as follows: When the cover B is removed and the vessel A is in a vertical position, then the wood or like material can be readily placed in position in the vessel A, and when the latter is filled with the wood then the cover B is secured in place to close the vessel A. The latter is now swung into a horizontal position, so that the perforated pipes J are at the bottom, while the entrance-opening to the pipe K is at the top. Steam is now permitted to pass by way of the perforated pipes J into the vessel A to act on the wood contained therein with a view to carry on the destructive distillation of the wood; the vapors arising within the vessel being carried off by the pipe K, trunnion D, and pipe H to a condenser or like apparatus. After the process of distillation is completed the steam is shut off, the cover B is removed, and the vessel A is swung into a vertical position with the open end of the vessel downward, so that the residue of the process of distillation is dumped into a conveying-trough or the like for carrying the residue to a suitable place of discharge. After this has been done the vessel A can be returned to the original position to allow refilling and then the above-described operation is repeated.

35 From the foregoing it will be seen that the retort can be quickly filled with the wood or other substance to be treated and the destructive process of distillation can be carried on and the residue thereof dumped in a comparatively short time and without requiring skilled labor.

The apparatus is very simple and durable in construction and is not liable to get easily out of order.

45 Having thus described my invention, I claim as new and desire to secure by Letters Patent—

1. A retort for the destructive distillation of wood, comprising a closed vessel having a removable cover at one end, hollow trunnions on the sides of the vessel approximately at the middle thereof, one of the trunnions being connected with a steam-supply, perforated pipes arranged parallel

with each other and extending lengthwise in the vessel at one side thereof and adjacent to the inner surface, a transverse pipe within the vessel and connecting said perforated pipes, a pipe leading from said transverse pipe to the outside of the vessel and connecting with the trunnion connected with the steam-supply, and a connection between the other trunnion and the interior of the vessel at a point opposite the said perforated pipes.

2. A retort for the destructive distillation of wood, comprising a closed cylindrical vessel having a removable cover at one end, hollow trunnions at opposite sides of the vessel approximately at the middle thereof, the said trunnions being mounted to turn in suitable bearings to bring the vessel into a vertical position for filling, into a horizontal position for carrying on the destructive process of distillation, and into an inverted position for dumping the residue of the process of distillation, one of said trunnions being connected with a steam-supply and provided with an integral lateral outlet, two perforated parallel pipes within the vessel, the pipes extending lengthwise of the vessel at one side thereof and adjacent to the inner surface, the said perforated pipes extending along the bottom of the vessel when the latter is in the horizontal position for carrying on the process of distillation, a transverse branch pipe within the vessel and connecting the perforated pipes at or near the middle thereof, a pipe leading from the branch pipe to the exterior of the vessel and connecting with the lateral outlet of the trunnion connected with the steam-supply, the other trunnion being the cutlet-trunnion for the escape of the vapors, and having an integral lateral inlet, a pipe leading from the interior of the vessel at a point opposite the said perforated pipes and connected with the lateral inlet of said outlet-trunnion, and means for forming a tight joint between the said cover and the corresponding end of the vessel.

In testimony whereof I have signed my name to this specification in the presence of two subscribing witnesses.

PERCY JACKSON.
